LATCH

Clarence B. Jefferies, 5134 Darnell,
Houston, Tex. 77035

Filed Nov. 12, 1969, Ser. No. 20,042

Term of patent 14 years

Int. Cl. D8—03

U.S. Cl. D8—261

FIG. 1 is a view from the side of a latch incorporating my design; and

FIG. 2 is a view from the top.

The broken lines in FIG. 1 indicate the opposite ends of a chain to be connected by the latch.

I claim:

The ornamental design for a latch, substantially as shown and described.
